GIFT PACKAGE FOR GOLF ACCESSORIES

James C. Taylor, Rte. 1, Box 297D,
San Marcus, Tex. 78666

Filed Aug. 24, 1970, Ser. No. 24,657

Term of patent 14 years

Int. Cl. D9—03

U.S. Cl. D9—193

FIG. 1

FIG. 3

FIG. 1 is a front elevation of a gift package for golf accessories showing my new design;

FIG. 2 is a side perspective view thereof; and

FIG. 3 is a side elevation thereof.

The unillustrated backside of the package is substantially flat and unornamented.

I claim:

The ornamental design for a gift package for golf accessories, substantially as shown and described.
